TABULATING MECHANISM FOR CALCULATING-MACHINES.

1,259,929.

Specification of Letters Patent. Patented Mar. 19, 1918.

Application filed May 18, 1917. Serial No. 169,586.

To all whom it may concern:

Be it known that I, OTTO THIEME, a citizen of the United States, residing at the city of St. Louis, State of Missouri, have invented 5 a certain new and useful Improvement in Tabulating Mechanism for Calculating-Machines, of which the following is a full, clear, and exact description, such as will enable others skilled in the art to which it applies to make and use the same, reference being had to the accompanying drawings, forming part of this specification, in which—

Figure 1 is a side elevational view partly in section of my improved tabulating mechanism as applied to combined adding and typewriting machines.

Fig. 2 is a top plan view of part of the keyboard showing the motor bar and tabulating keys.

Fig. 3 is a side elevational view of the keys shown in Fig. 2 illustrating the connections of said keys.

Fig. 3^a is a detail view of the lock for the tabulator disabling mechanism.

Fig. 4 is a detail view of certain of the parts operated by the tabulating key and the motor key.

Fig. 5 is a detail view showing certain of the parts illustrated in Fig. 4 in a changed position.

Fig. 6 is a vertical sectional view showing the upper end of the tabulating bar and its connections in elevation.

Fig. 7 is an enlarged front elevational view of the upper end of the tabulating bar and its connections.

Fig. 8 is a sectional view on line 8—8 of Fig. 7.

Fig. 9 is a detail view of one of the controlling members of the tabulating bar.

Fig. 10 is a detail view of another one of the controlling members of the tabulating bar.

Fig. 11 is a front elevational view showing the parts in a changed position from that illustrated in Fig. 7.

Fig. 12 is a detail view of one of the adjustable tabulating blocks arranged on the paper carriage.

My invention relates to a new and useful improvement in tabulating mechanisms for calculating machines which is designed particularly for use in connection with a combined adding and typewriting machine, 55 commercially known as the Moon-Hopkins

billing machine, such as disclosed in French Patent No. 383,719 granted January 16, 1908, to Hubert Hopkins, and application for United States Letters Patent filed April 9, 1906, Serial No. 310,739.

One of the features of my present invention is to provide a lock for the tabulating bar to hold it in its lowered and raised positions; another of the features of my invention is to provide a multiple control for the tabulating mechanism which, briefly stated, may be divided into four parts; first, the positioning of the tabulating bar directly upon the operation of the tabulating key; this may be done before any operation of the adding mechanism of the machine; second, positioning the tabulating bar coincidentally with the operation of the adding machine and near the end of the final movement thereof, i. e., after the recording devices of the adding machine have been operated; third, temporarily disabling the tabulating bar from movement while the adding machine performs a complete operation; and, fourth, permanently disabling the tabulating bar from any operation incident to the depression of the motor key for effecting an operation of the adding mechanism.

Other features of my invention reside in the locking and releasing devices for the several parts whereby each is held in position until its proper function is performed and then restored, or permitted to be restored, to normal position in readiness for another operation.

In the drawings, 1 indicates a platen of a laterally movable paper carriage and 2 are the keys of the typewriting mechanism for recording letters and words and figures upon the paper as in writing in the item and date on a bill or invoice, etc. 3 is a rack on the carriage with which meshes a pinion 4 on the upper end of a shaft 5, said shaft being designed to be coupled to a constantly rotating shaft 6 through the medium of a clutch for back-spacing or returning the carriage to its normal position by the use of mechanism such as shown in United States Letters Patent No. 1,096,074 granted to me May 12, 1914, (back spacing mechanism for paper carriages) and United States Letters Patent No. 1,120,862 granted to me December 15, 1914, (carriage return mechanism). The motor drive for the calculating ma-

chine, which motor also drives the carriage return and back-spacing mechanisms above referred to, is shown in the Hubert Hopkins Patent No. 1,025,698 granted May 7, 1912, and with respect to these various mechanisms, parts of which are shown in the accompanying drawing, it is unnecessary to give full and complete description except to state that 6 is the motor which, through suitable gearing, drives the shaft 7, said shaft carrying a crank arm 8 to which is attached a link 9, the upper end of said link being connected to a rock arm 10 on the rock shaft 11 which carries a locking member 12 having a pin 13. This pin cooperates with a tappet 14 on the end of a rock arm 15 mounted on rock shaft 16, on which shaft is a forwardly extending rock arm 17 carrying an adjustable impinging member in the form of a screw 18 designed to lift the tabulating bar under certain conditions, as will hereinafter appear, whereby the crank arm 8 which is caused to make one complete revolution is under control of a bar 19 having a laterally projecting pin designed to cooperate with an inclined face on the upper edge of a bar 20. The details of this motor clutch mechanism are fully shown and described in the Hubert Hopkins Patent No. 1,025,698, before referred to, and as they form no part of my present invention, they need not be further described here. It is necessary, however, in connecting the crank arm 8 to the motor to effect an operation of the adding machine, to move the bar 20 forwardly where it remains while the motor key is depressed and just before the crank arm reaches a full completion of its revolution, means, shown in the Hubert Hopkins patent last mentioned, are provided for restoring the motor bar 20, or such other bars as may, when operated, raise the clutch bar 19 and coincidentally with this restoration of the bar 20, move said bar rearwardly and at the same time raise the motor key connected thereto. Bar 20 is connected by a rod 21 to a bell crank 22 which bell crank may be operated by the motor key 23 (see Figs. 1, 2, and 3). Thus when the key 23 is depressed bar 20 is pulled forwardly, clutch bar 19 is raised, and crank shaft 8 is caused to make a full revolution and just prior to the completion of this full revolution, bar 20 is caused to move rearwardly to permit the clutch bar 19 to descend, thereby disengaging the motor clutch.

In making out bills and invoices where the dates and items are written in on the typewriting mechanism, a tabulating key marked 25 may be depressed to release the paper carriage permitting its leftward movement until arrested in a position where the amount of the item set up on the digit keys of the typewriter is to be registered in the totalizer and recorded in the column of

figures at the right of the items so that a correct addition of all the items may be obtained and recorded at the bottom thereof. The use of the tabulating mechanism is of course old in typewriters and tabulating devices have been employed in combined adding and typewriting machines in the manner just referred to and now about to be described. The tabulating key 25 is connected to a bell crank lever 26 to which is attached a rod 27 having its rear end connected to a rocking lever 28 mounted in a bracket secured to the base of the machine (see Fig. 3). This bell crank lever 28 has an upward extension at its rear end to which is connected a bar 29, said bar having a slot in its upper end through which slot passes a rod 30. Normally this rod 30 lies in the lower end of the slot of bar 29 and consequently while the inner end of rod 30 may be raised, moving idly in said slot, the lifting of bar 29 will cause the inner end of bar 30 to be raised. The inner end of bar 30 finds support in the lower end of tabulating bar 31, while the outer end of bar 30 finds support in a bracket 32 secured to the frame of the machine (see Fig. 4).

The operation of the tabulating key 25 through the instrumentalities just above described simply results in lifting the tabulating bar 31 and in this respect, by lifting said bar to a raised position, places its upper end in the path of an adjustable stop carried by a rod on the paper carriage. The bar 31 has its lower end guided by a plate 32 secured to a cross arm bar 33 of the machine. A spring 34 tends to hold bar 31 in its lowered position while another spring 34 connected near its upper end tends to pull the upper end of the tabulating bar toward the right. The upper end of the tabulating bar is guided by a slot and pin connection in a housing 35 arranged on the top frame plate 36 of the typewriting machine, said bar being provided with a lateral projection 37 which normally is pulled against the face of the lug 38 fixed in the housing 35. When the bar 31 is raised by the tabulating key, as shown by dotted lines in Fig. 6, the lateral projection 37 when it reaches a point above the lug 38 will permit the upper end of the tabulating bar to be moved rightwardly under the impelling action of spring 34, said lateral projection, by thus passing above the lug 38, locking the tabulating bar in its raised position. In being raised and moving rightwardly, as above described, the tabulating bar will operate a lever 39 whose lower end engages a notch in a guard bar 40. A spring 41 tends to hold the lower end of lever 39 in engagement with the guard bar at all times. A spring 42 tends to lift the guard bar at all times, said guard bar having a head portion 40a lying across the lug 38 and an inclined edge 40b, as shown in

Figs. 6, 8, 10 and 11. Thus whenever the tabulating bar 31 is raised the strength of spring 34^a will rock the restraining lever 39 when the tabulating bar is raised, such releasing lever, upon being rocked, releasing the guard bar and permitting it to rise to the position shown in Fig. 11. 45 indicates a restoring lever for the guard bar pivotally mounted on the housing 35 and having a slot 45^a for receiving a pin 40^a carried by a cross arm on the guard member 40. The upper end of guard lever 45 is provided with a lateral projection whose side edges are beveled or inclined as shown in Fig. 9, this lateral projection normally lying above and slightly to one side of the beveled upper end of the tabulating bar 31. By the slot and pin connection, just above described, the guard bar and its restoring lever move upwardly in unison as shown in Fig. 11, the guard bar serving to prevent rebound of the carriage by rising behind the lug 46^a after said lug passes thereover. The lug, after passing over the upper end of the tabulating lever, engages the restoring lever 45 and fully depresses the guard bar 40 to its lowest position, where it is locked by the lever or bar 39. In moving leftwardly, the tooth 46^a of the adjustable block 46 will thus first strike the inclined face 40^b of the guard member 40, depressing the same and the guard lever 45 (but not to their fullest extent), until tooth 46^a is arrested by the upwardly projecting end of the tabulating bar, at which time the guard member is again in its elevated position to prevent rebound of the carriage. Before reaching its final point of arrest, the tooth 46^a will move the upper end of the tabulating bar leftwardly until the projection 37 passes beyond the lug 38 at which time the spring 34 will draw the tabulating bar downwardly. The movement of the upper end of tabulating bar leftwardly will enable the lever 39 to reengage the guard bar 40 when the restoring lever 45 moves it to its lowest position, whereby lever 39 will lock said parts in their full depressed position. The tabulating bar 31 has a shoulder 31^a near its upper end which engages a rocking plate 50 so as to move the escapement pinion rearwardly out of mesh with the rack on the paper carriage when the tabulating bar is lifted. When the tabulating bar is depressed, the spring 51 bearing against the upper end of shaft 5 reengages the escapement pinion with the rack which thereby becomes a lock for the paper carriage to prevent further leftward movement thereof.

Each of the blocks 46 is provided with a set screw 46^b designed to engage a flat upper face of shaft 47, the rearwardly extending portion of block 46 being provided with teeth or projections to engage notches in the track rail 52 of the paper carriage whereby

the tabulating blocks are locked in their adjusted positions. To change the position of the tabulating blocks, it is only necessary to loosen the screws, tilting them forwardly until the teeth are disengaged from the notches in the track rail when the blocks may be adjusted longitudinally the shaft 47 and can be tilted backwardly and locked in their new positions.

The tabulating key 25 lifts and positions 75 the tabulating bar 31 independently of the operation of any motor key. The subsequent depression of the motor key 60, to be hereafter described, will cause the adding mechanism to be operated to record numbers on 80 the paper carried by the platen in such column or position on the paper as may have been determined by the operation of the tabulating key, if the same had been depressed. The release of the tabulating bar 85 upon being moved leftwardly from its raised and locked position will enable it to be restored by the action of spring 34 independently of any operation of the motor driven adding machine and consequently such restoration occurs coincidentally and immediately following the depression of the tabulating key.

The motor key 23, before described, rocks the arm 17, by first raising and then lowering said arm, such rocking movement occurring just before the final movement, or what might be termed the back stroke of the power driven rock shaft 11. The bar 30, before referred to, is provided with a collar 100 30^a which collar normally lies in the path of movement of the adjustable lifting screw 18 and consequently as the bar 30 is mounted in the tabulating bar 31, the upward movement of arm 17 will raise the tabulating 105 bar; hence, by depressing the motor key 23 and independently of any previous operation of the tabulating key 25, the adding mechanism will be caused to make an effective operation in registering and recording 110 an item or a number after which, and just before the final completion of such adding machine movement, the tabulating bar will be restored. This automatic operation of the tabulating mechanism following the 115 registration of and recording of a number in and by the adding mechanism is of importance in connection with statistical work, wherein the numbers so recorded are to be arranged in column order. It may be desirable at times to operate the tabulating 120 mechanism automatically and in connection with the operation of the motor key, before an effective movement of the adding mechanism, as in statistical work, but at other 125 times it is desirable to operate the adding mechanism independently of any operation of the tabulating mechanism. In other words, while the tabulating mechanism is in readiness for operation upon the depre- 130

sion of one motor key (motor key 23), the depression of another motor key (motor key 60) will disable the tabulator control and prevent the raising of the tabulating bar.

5 The motor key 60 is arranged upon the forward end of the bell crank lever 61 having a rearward extension to which is pivotally connected a link 62 said link having a slot and pin connection with the bell crank lever 10 22 of the motor key 23. A spring 63 tends to hold the motor key 60 in its normally raised position. However, when the motor key 60 is depressed it will rock the bell crank 22 and move the motor bar 20 forwardly 15 which is equivalent to a depression of the motor key 23. When the motor key 23 is depressed, through the slot and pin connection just above referred to, the motor key 60 will not be depressed. In other words, 20 key 23 operates its connections without operating any of the connections of the key 60; but depression of the key 60 not only operates its connections but also the connections of key 23. Rod 64 is one of the 25 connections operated by the key 60, said rod being connected to the lower end of a rocking lever 65, the upper end of which rocking lever being located in front of a T-shaped lever 66 pivoted on a lug extending 30 from the frame bar 33. The forwardly extending member of this T-shaped lever is provided with an opening which engages a pin 30^a on rod 30 and consequently when motor key 60 is depressed, rod 30 will be 35 moved rightwardly, carrying with it the collar 30^a so as to locate said collar to one side, the right, of the path of movement of the lifting screw 18. Hence, while the collar 30^a may be located over the lifting screw 18 40 in a position to lift the tabulating bar 31 whenever the motor key 23 is depressed, the depression of the motor key 60 will move the collar 30^a rightwardly out of the path of the lifting screw 18 and thus disable the tabulating bar lifting mechanism. By this 45 means, the adding mechanism may be made to operate through the motor driven connections controlled by the motor key 60, while the tabulating bar remains inactive.

50 Means are provided for locking the collar 30^a in its displaced position during the time that the motor key 60 is depressed and until just before the adding machine mechanism completes its final movement. It has been 55 described that when the motor key 23 is depressed, the lifting of the tabulating bar incident to such depression will occur just before the completion of the final stroke of the main operating shaft of the adding machine. It follows, therefore, that to hold the 60 collar 30^a displaced during the vibration of the lifting screw 18, or at least the upward stroke thereof, that such displacing means should not be released until the lifting screw 65 is either nearing the upward limit of its movement or has started to descend below the collar 30^a. The locking mechanism for the collar 30^a and the rod 30 on which it is carried, comprises a bar 70 having one end connected to the T-shaped lever 66 and the other end guided by a slot and pin connection with the frame bar 33. This bar 70 is provided with a shoulder 70^a which cooperates with a shoulder 71^a on a locking pawl 71. This locking pawl is normally pulled 75 down by a spring 72 so that when the bar 70 is moved rightwardly, as shown in Fig. 5, the end of pawl 71 will drop behind the shoulder 70^a, as shown in said figure, its downward movement being arrested by a 80 lug or bracket 33^a extending from the frame bar 30. 74 indicates a complementary locking pawl pivotally mounted on the extension 33^a and whose end is normally held raised by a spring 75. A lateral extension 74^a projecting under the lug 33^a limits the upward movement of the forward end of this locking member 74. (See Fig. 3.) It has been 85 before described that the shaft 11, which is the main operating shaft of the adding mechanism, is rocked first forwardly and then backwardly at every complete revolution of the motor driven crank arm 8. On shaft 16, which is part of the adding, machine mechanism, is a rock arm 76 on which 90 is mounted a bar 77 provided with a pin 78 lying under the rear end of the locking member 74. When the motor key 60 is depressed, it will, through the connections above described, move the bar 70 rightwardly until 100 the end of pawl 71 lies behind the shoulder 70^a, thus locking said bar in its rightward position and consequently holding the collar 30^a displaced and out of the path of the lifting screw 18. Upon the depression of 105 the motor key 60, the motor will rock the shaft 16 causing the bar 77 to descend and consequently pin 78 will be moved downwardly away from the rear end of the locking member 74, thus permitting the forward 110 end of said locking member to rise under the impelling action of its spring so as to locate the forward end of the member 74 behind the shoulder 70^a. The power of spring 75 is sufficient to lift the end of the locking 115 pawl 71 above the shoulder 70^a so that this locking pawl is raised out of locking engagement with the bar 70 and said bar 70 is restrained from rightward movement by the front end of member 74. Of course, there 120 is sufficient clearance of the parts to permit this operation, that is, the original displaced position of the bar 70 when it is temporarily held by the end of pawl 71 provides sufficient clearance for the movement of the forward end of the locking member 74 behind the shoulder 70^a; and the lifting movement of the forward end of the locking member 74 is sufficiently great to carry the end of the locking pawl 71 above the shoulder of the 125 130

bar 70 permitting a slight leftward movement of bar 70 to take up the clearance previously provided and which slight leftward movement of bar 70 will locate the shoulder 5 70^a under the end of the locking pawl 71 (Fig. 3^a). When the bar 77 rises, and just before it completes its final movement, the pin 78 will engage the rear end of the locking members 74 lifting it and depressing 10 the forward end out of engagement with the shoulder 70^a. This depression of the forward end of the member 74 continues until about the time all the parts are in their home position when the forward end of said rocking member 74 will release bar 70 and permit 15 its leftward movement to normal position.

The parts above described presuppose desired operations of the machine wherein, (1) the tabulating mechanism can be independently actuated before any operation of the adding machine; (2) the automatic operation of the tabulating mechanism as an incident to the operation of the adding mechanism upon the depression of a given motor 20 key; and (3) the displacement of the control devices of the tabulating mechanism whereby it is inactive during the operation of the adding mechanism incident to the depression of another motor key.

30 It is sometimes desirable to permanently disable the tabulating mechanism from any motor key control and this is accomplished by providing the rod 30 with a button 30^a at its outer end by which said rod may be manipulated by the operator. By pulling the rod outwardly, or to the right, an annulus 30^a is brought in alignment with the locking bell crank 80 pivotally mounted upon the bracket 32 and whose lower end is 35 designed to enter the annulus 30^a and prevent inward movement of the rod 30. A spring 81 is connected to the lower end of the bell crank to hold it in its locked position. By thus permanently holding the rod 40 45 30 in its rightward position, the collar 30^a is displaced with respect to the lifting screw 18 and consequently the operation of the motor driven parts cannot effect tabulation. When it is desired to restore rod 30 to an 50 operative position, the bell crank 80 is operated to release said rod which will move inwardly under the impelling action of the spring connected to the T-shaped lever 66 to an operative position.

55 In the Hubert Hopkins French patent, before referred to, and United States application Serial No. 310,739, there is illustrated a multiplying mechanism, the operation of the multiplying keys of which lifts the bar 19 independently of any depression of the motor key. In other words, the operation of any one of the multiplier keys indicated at 90, Fig. 2, is equivalent, so far as raising 60 the bar 19 is concerned, to depressing one of 65 the motor keys 23 or 60, with this difference,

however, that in said French patent means are provided for causing the crank arm 8 to make two complete revolutions instead of one, when the multiplier keys marked "2" to "9" are depressed. When the multiplier 70 keys "1" or "0" are depressed, said crank arm will make only one revolution. We are not concerned in this application with the multiplying mechanism nor the means controlled by the multiplier keys for causing the 75 crank arm to make one or two revolutions as the case may be, but we are concerned with the fact that when the adding machine is operating in the performance of multiplication, if the collar 30^a is located over the 80 lifting screw 18, the tabulating bar will be raised at each rocking movement of the shaft 16, unless of course the operator takes the precaution to pull the rod 30 outwardly into what has been designated as the permanently 85 locked disabling position of the tabulating mechanism before starting the multiplying operation. To take care of this possible oversight on the part of the operator, means are provided to disable the tabulating mechanism whenever multiplication is being performed. This means consists of a bar 91 which bar is identified with the multiplying devices of the machine and vibrates at every revolution of the crank shaft 8 in the performance of multiplication. Bar 91 is connected to a bell crank lever 92 which in turn operates upon another bell crank lever 93 which latter has one of its arms extending down behind one member of the T-shaped 100 lever 66. By this construction, whenever the bar 91 is raised, it will operate the T-shaped lever 66 the same as if the motor key 60 was depressed, thereby displacing rod 30 and its carried collar 30^a, the locking devices 105 co-operating with the rod 70 and being released by the pin 78 in the manner heretofore described.

What I claim is:

1. In a tabulating mechanism for calculating machines, the combination of a paper carriage and its tabulating stop, a tabulating bar capable of being positioned in the path of movement of said stop to arrest the carriage in a predetermined position, a key 110 for manually positioning said tabulating bar, an adding mechanism, a motor drive for said adding mechanism, and a key for controlling said motor drive, said last mentioned key having connections whereby said tabulating 115 bar may be operatively positioned coincidentally with the depression of said motor key for effectively connecting said motor and said adding mechanism.
2. In a tabulating mechanism for calculating machines, the combination of a paper carriage and its tabulating stop, of a tabulating bar capable of being positioned in the path of movement of said stop, an adding mechanism, a motor drive for said adding 120 125 130

- 6 mechanism, a key for rendering said motor drive effective with respect to said adding mechanism, means operated by said last mentioned key for also rendering the tabulating mechanism effective, another key in control of said motor drive for rendering the same effective with respect to said adding mechanism, and means operated by the said last mentioned key for disabling the tabulating mechanism.
3. In a tabulating mechanism for calculating machines, the combination of a paper carriage and its tabulating stop, of a tabulating bar designed to coöperate with said stop to arrest the carriage in a predetermined position, an adding mechanism, a motor drive for said adding mechanism, a key for rendering said motor drive effective with respect to said adding mechanism, means operated by a moving part of said adding mechanism for rendering said tabulating mechanism effective, and means operated by said key for disabling or rendering ineffective the moving part of said adding mechanism which operates said tabulating mechanism.
4. In a tabulating mechanism for calculating machines, the combination of a paper carriage and its tabulating stop, of a tabulating bar capable of being positioned to coöperate with said stop to arrest the carriage in a predetermined position, an adding mechanism including a movable part designed to position said tabulating bar, said adding mechanism also including another part for rendering said tabulator positioning mechanism ineffective in certain operations of the adding machine.
5. In a tabulating mechanism for calculating machines, the combination of a paper carriage and its tabulating stop, of a tabulating bar capable of being positioned to coöperate with said stop to arrest the carriage in a predetermined position, an adding mechanism including a part designed to position said tabulating bar, and dual means for disabling the movable part of the adding mechanism, whereby said tabulating mechanism is rendered inoperative during certain operations of the machine.
6. In a tabulating mechanism for calculating machines, the combination of a paper carriage and its tabulating stop, of a tabulating bar capable of being positioned to coöperate with said stop to arrest the carriage in a predetermined position, an adding mechanism including a part designed to position said tabulating bar, and independently operative dual means for disabling the movable part of the adding mechanism, whereby said tabulating mechanism is rendered inoperative during certain operations of the machine.
7. In a tabulating mechanism for calculating machines, the combination of a paper carriage and its tabulating stop, of a tabulating bar capable of being positioned to coöperate with said stop to arrest the carriage in a predetermined position, an adding mechanism including a movable part designed to position said tabulating bar, and a displaceable member coöperating with said tabulating bar to position the same whenever said displaceable member lies in the path of movement of the movable part of said adding mechanism.
- per carriage and its tabulating stop, of a tabulating bar capable of being positioned to coöperate with said stop to arrest the carriage in a predetermined position, an adding mechanism including a movable part 70 designed to position said tabulating bar, a motor drive for said adding mechanism, a key for rendering said motor drive effective with respect to said adding mechanism whereby said tabulating mechanism is operated in conjunction with said adding mechanism upon the operation of said key, and dual means for rendering said tabulating mechanism inoperative during certain operations of the machine, and a key for rendering one of said dual disabling means operative.
8. In a tabulating mechanism for calculating machines, the combination of a paper carriage and its tabulating stop, of a tabulating bar designed to coöperate with said stop to arrest the carriage in a predetermined position, an adding mechanism, a motor drive for said adding mechanism, a key for rendering said motor drive effective 80 with respect to said adding mechanism, means operated by a moving part of said adding mechanism for rendering said tabulating mechanism effective, and means for permanently disabling the moving part of 85 said adding mechanism which operates the tabulating mechanism whereby said tabulating mechanism is rendered inoperative during certain operations of the machine.
9. In a tabulating mechanism for calculating machines, the combination of a paper carriage and its tabulating stop, of a tabulating bar designed to coöperate with said stop to arrest the carriage in a predetermined position, an adding mechanism, a motor drive for said adding mechanism, a key for rendering said motor drive effective 90 with respect to said adding mechanism, means operated by a moving part of said adding mechanism for rendering said tabulating mechanism effective, and means for permanently disabling the moving part of 95 said adding mechanism which operates the tabulating mechanism whereby said tabulating mechanism is rendered inoperative during certain operations of the machine.
10. In a tabulating mechanism for calculating machines, the combination of a paper carriage and its tabulating stop, of a tabulating bar capable of being positioned to arrest said carriage in a predetermined position, an adding mechanism including a movable part 100 designed to operate said tabulating bar, and a displaceable member coöperating with said tabulating bar to position the same whenever said displaceable member lies in the path of movement of the movable part of said adding mechanism.

and means for operating said displaceable member and moving it to a position wherein the movable part of the adding mechanism may move without positioning said tabulating bar.

11. In a tabulating mechanism for calculating machines, the combination of a carriage and its tabulator stop, of a tabulator bar designed to coöperate with said stop to arrest the carriage in a predetermined position, a rod coöoperating with said tabulating bar and being provided with a part lying in the path of movement of a movable part of an adding mechanism, an adding mechanism including the movable part referred to, and means for moving said rod and its carried part so that when the moving part of the adding mechanism operates, it will not operate the tabulating mechanism.
12. In a tabulating mechanism for calculating machines, the combination of a paper carriage and its tabulating stop, a tabulating bar capable of being positioned to arrest said carriage in a predetermined position, an adding mechanism including a movable part designed to operate said tabulating bar, and a displaceable member coöperating with said tabulating bar to position the same whenever said displaceable member lies in the path of movement of the movable part of said adding mechanism, and means for operating said displaceable member and moving it to a position wherein the movable part of the adding mechanism may move without positioning said tabulating bar, said means including a T-shaped lever for controlling the position of said displaceable part, and a key for moving said T-shaped lever to its displacing position.
13. In a tabulating mechanism for calculating machines, the combination of a paper carriage and its tabulating stop, a tabulating bar capable of being positioned to arrest said carriage in a predetermined position, an adding mechanism including a movable part designed to operate said tabulating bar, and a displaceable member coöperating with said tabulating bar to position the same whenever said displaceable member lies in the path of movement of the movable part of said adding mechanism, and means for operating said displaceable member and moving it to a position wherein the movable part of the adding mechanism may move without positioning said tabulating bar, said means including a T-shaped lever for controlling the position of said displaceable part, and a movable part of said adding mechanism for operating said T-shaped lever to its displacing position.

14. In a tabulating mechanism for calculating machines, the combination of a carriage and its tabulator stop, of a tabulator bar designed to coöperate with said stop to arrest the carriage in a predetermined posi-

tion, a rod coöperating with said tabulating bar and being provided with a part lying in the path of movement of a movable part of an adding mechanism, an adding mechanism including the movable part referred to, means for moving said rod and its carried part so that when the moving part of the adding mechanism operates, it will not operate the tabulating mechanism, and means for temporarily locking said rod and its carried part in their displaced position during the major portion of the movement of said adding mechanism.

15. In a tabulating mechanism for calculating machines, the combination of a carriage and its tabulator stop, of a tabulator bar designed to coöperate with said stop to arrest the carriage in a predetermined position, a rod coöoperating with said tabulating bar and being provided with a part lying in the path of movement of a movable part of an adding mechanism, an adding mechanism including the movable part referred to, means for moving said rod and its carried part so that when the moving part of the adding mechanism operates, it will not operate the tabulating mechanism, and means for permanently locking said rod and its carried part in their displaced position during the entire movement of said adding mechanism.

16. In a tabulating mechanism for calculating machines, the combination of a carriage and its tabulator stop, of a tabulator bar designed to coöperate with said stop to arrest the carriage in a predetermined position, a rod coöoperating with said tabulating bar and being provided with a part lying in the path of movement of a movable part of an adding mechanism, an adding mechanism including the movable part referred to, means for moving said rod and its carried part so that when the moving part of the adding mechanism operates, it will not operate the tabulating mechanism, and means for temporarily locking said rod and its carried part in their displaced position during the major portion of the movement of said adding mechanism, said temporary locking means comprising a pawl which initially locks said rod and its carried part in a displaced position, and a member under control of a moving part of said adding mechanism for releasing said rod from the restraint of said pawl, said member constituting a supplementary lock for said rod until operated by the moving part of the adding mechanism to release the rod.

17. In a tabulating mechanism for calculating machines, the combination of a carriage and its tabulator stop, of a tabulator bar designed to coöperate with said stop to arrest the carriage in a predetermined position, a notched rod coöoperating with said tabulating bar and being provided with a

part lying in the path of movement of a movable part of an adding mechanism, an adding mechanism including the movable part referred to, means for moving said rod and its carried part so that when the moving part of the adding mechanism operates, it will not operate the tabulating mechanism, and means for permanently holding said rod and its carried part in a displaced position, 10 said means comprising a spring pressed member engaging in the notch of said rod.

18. In a tabulating mechanism for calculating machines, the combination of a paper carriage and its tabulating stop, of a tabulating bar designed to coöperate with said stop to arrest the carriage in a predetermined position, an adding mechanism, a mo-

tor drive for said adding mechanism, a key for rendering said motor drive effective with respect to said adding mechanism, means 20 operated by a moving part of said adding mechanism for rendering said tabulating mechanism effective, a guard coöperating with the upper end of said tabulating bar which guard member is rendered operative 25 by the positioning movement of said tabulating bar, and means operating independently of said tabulating bar and said adding mechanism for restoring said guard member to its inoperative position. 30

In testimony whereof I hereunto affix my signature this 10th day of May, 1917.

OTTO THIEME.
